TIRE

Leonard C. Youngblood, Grosse Pointe Park, Mich.,
assignor to United States Rubber Company, New York,
N.Y., a corporation of New Jersey

Filed Sept. 25, 1964, Ser. No. 31,872

Term of patent 14 years

(Cl. D90—20)

Fig. 1

*Fig. 3**Fig. 5**Fig. 4**Fig. 2*FIG. 1 is a perspective view of a tire embodying my new design, it being understood that the full line portion is repeated throughout the circumference of the tire, shown by means of broken lines;

FIG. 2 is an enlarged fragmentary elevational view of the full line sidewall portion shown in FIG. 1;

FIG. 3 is a further enlarged fragmentary plan view of the full line tread portion shown in FIG. 1;

FIG. 4 is a sectional view taken substantially on the plane indicated by line IV-IV of FIG. 3, but also on the same scale as FIG. 2;

FIG. 5 is a detailed sectional view taken substantially on the plane indicated by line V-V of FIG. 4.

The dominant features of my design reside in those portions shown in full lines in the drawings.

I claim:

The ornamental design for a tire, substantially as shown and described.
